UNITED STATES PATENT OFFICE.

FRANZ LOUIS WÄCHTLER, OF GROSSENHAIN, GERMANY, ASSIGNOR TO CROMPTON & KNOWLES LOOM WORKS, A CORPORATION OF MASSACHUSETTS.

LOOM.

No. 918,801.

Specification of Letters Patent.

Patented April 20, 1909.

Application filed April 27, 1904. Serial No. 205,161.

To all whom it may concern:

Be it known that I, FRANZ LOUIS WÄCHTLER, a subject of the King of Saxony, residing at 24 Dresdenerstrasse, Grossenhain, in 5 the Kingdom of Saxony and Empire of Germany, have invented new and useful Improvements in and Relating to Weft-Replenishing Looms, of which the following is a specification.

10 My invention relates to looms and comprises a device which, in common looms, enables the operating shuttle to be replaced by a shuttle with a fresh filling, and which, in the manufacture of cross-striped fabrics, for 15 the purpose of introducing a differently colored weft, enables the operating shuttle to be replaced by a shuttle with a filling of this color, without stopping the loom. Applied to change looms the device enables each of 20 the operating shuttles to be exchanged, according to requirements and in a predetermined manner, for a shuttle with the same or a different weft thread, also without stoppage of the loom. In case the pattern to be 25 woven comprises more colors than the number of shuttles which may be placed at the same time in the respective shuttle changing mechanism, the device, owing to the exchangeability of each shuttle for any other 30 desired shuttle without stopping the loom, may also be employed for carpet looms and the like.

According to my said invention I arrange on one side of the loom, preferably on the 35 right hand side, two special shuttle boxes or cells in addition to the common shuttle box or cell in the case of loom for plain fabric. In the case of change looms, I arrange the two special cells on one side of the loom. One of 40 the special cells is placed in line with the shuttle race, instead of the ordinary cell which would otherwise take up the shuttle now to be removed, in order to catch this shuttle for subsequent removal by hand, 45 whereupon it is replaced, prior to the next pick, by the second special cell holding the fresh shuttle, the place of the latter cell being then taken by the ordinary cell immediately after the pick.

50 In the case of change looms the arrangement must be such that the two special cells will be placed in line with the shuttle race one after the other just at the moment when the shuttle to be removed is thrown to that 55 side of the loom where the two special cells

are situated. For this purpose I provide a special device comprising a card hereinafter named a controlling card. This card controls the change of the shuttles, in lieu of the ordinary change card, in accordance with 60 the successive locations of the special cells, as soon as the shuttle to be removed is thrown to the side of the special cells. In this case the action upon the shuttle changing device by the controlling card is com- 65 monly prevented by separate locking devices corresponding each to one of the operating shuttles and adapted to be released by hand.

With the object of rendering the device available for all cases, that is to say not only 70 where two similar wefts follow each other at the moment the shuttle is exchanged, such as is requisite if the special cells are displaced one immediately after the other, I provide two controlling cards, namely one card for 75 each special cell. Instead of these two cards, use may also be made of a single card with two sets of needles, each set corresponding to a special cell. In this case it is necessary that the two controlling cards or the two sets 80 of needles shall be dependent on each other in their action in such a manner that the cell designed to catch the shuttle to be removed shall first be located in line with the shuttle race. This may be accomplished by 85 a motive power device, such as a spring, being wound up when the cell for the shuttle to be removed is located in line with the shuttle race, through the intervention of the corresponding controlling card or the correspond- 90 ing set of needles, the said motive power device effecting the coupling of the means for locating the cell which serves for the insertion of the fresh shuttle, the release of the motive power device taking place by the sec- 95 ond controlling card or by the second set of needles.

To facilitate the explanation of my invention, I have embodied it in a device shown in the accompanying drawings, to the precise 100 construction, however, I do not wish to be understood as limiting myself, it being obvious that changes of construction may be made without departing from the spirit of the invention and the scope of the claims.

In these drawings, Figure 1 is a front elevation of the entire device applied to a loom having a drop shuttle box mechanism of any desired construction on either side. Fig. 2 is 105 a side elevation of the device as seen from the 110

side of the special cells. Fig. 3 is a side elevation of the device as seen from the other side. Fig. 4 is a front elevation of the shuttle-changing mechanism with the special cells. Fig. 5 is a section on the line A—B of Fig. 4. Fig. 6 is a plan and partial section on the line C—D of Fig. 4. Fig. 7 is a view of the chain of controlling cards, detached. Fig. 8 is, on an enlarged scale, and partly in section, a front view of the controlling device. Fig. 9 is a plan of the same, and Figs. 10 and 11 are, on an enlarged scale, and partly in section, front elevations of the said controlling device in different positions so as to explain its mode of operation. In Figs. 8, 10 and 11 the sides and other parts of the frame are indicated by broken lines in order that the essential features of the invention may be clearly shown.

In the constructional form represented by way of example the two special cells Z^9 and Z^{10} are united with the cells Z^6 , Z^7 , Z^8 situated on the side from which the loom is driven and appertaining to a drop shuttle box mechanism arranged on both sides of the loom and having its other cells Z^1 , Z^2 , Z^3 , Z^4 , Z^5 , arranged on the other side of such loom.

The lifting box B comprising the cells Z^6 , Z^7 , Z^8 , Z^9 , Z^{10} and the lifting box A comprising the cells Z^1 , Z^2 , Z^3 , Z^4 , Z^5 are adapted to be moved independently of each other in the well known manner by any suitable change mechanism in accordance with the pattern so that one of the cells Z^1 , Z^2 , Z^3 , Z^4 , Z^5 , and one of the cells Z^6 , Z^7 , Z^8 will be located in line with the shuttle race (Figs. 1, 2, 4, 5 and 6). The cells Z^1 , Z^2 , Z^3 , Z^4 , Z^5 , Z^6 , Z^7 , Z^8 are of the ordinary construction, as shown by the cells Z^5 , Z^6 , Z^7 , Z^8 (in Figs. 4 and 5.) The rear wall 97 is common to all cells Z^6 , Z^7 , Z^8 , Z^9 . The front wall of each of the cells Z^6 , Z^7 , Z^8 is formed by a tongue or binder 98, 98', 98'', each of which is adapted to be turned in a horizontal plane upon a hinge 99, 99', 99'' furnished at one end in the usual way. To this turning movement, which is caused in the well-known manner by the entering shuttle, is opposed a spring 100 or 100', or 100'', whereby the entering shuttle is subjected to a brake action. The tongues or binders 98, 98', 98'', when the corresponding cell is at the height of the shuttle race, act in the well-known manner upon the feeler 101 arranged on a transverse shaft 101' which is supported in bearings on the lathe. At the other end of the transverse shaft 101' and rearwardly thereof is secured an arm 101'' connected by a rod, cord or the like, 102', with the catch or pawl 102 of the tappet 103 for the shuttle driver on the other side of the loom, the connection being such that the catch or pawl will be released, if a shuttle is in any one of the cells Z^6 , Z^7 , Z^8 , which cell is in line with

the shuttle race at the time of picking, the

finger 101 is pushed outwardly, and the rock shaft 101' is rocked, and through connection 100'' and the lever 101'', the pawl 102 is raised free from the tappet 103, allowing the tappet to revolve without operating the picker stick 104. Through a similar rock shaft and connection, the picking motion on the opposite side of the loom is operated in a similar manner, as is well understood. If however after the passage of a shuttle into one of the cells Z^6 , Z^7 , or Z^8 an empty cell as Z^9 is located in line with the shuttle race there will be no release of the catch or pawl 102, and the driver 104, according to the pattern, throws a shuttle, meanwhile placed in position through the top of the upper cell Z^9 , or through the outwardly extending open end of the cell Z^{10} , see Fig. 6, for this driver, to the side of the special cells Z^9 , Z^{10} .

The cell Z^9 is the one wherein the shuttle is put which replaces the shuttle to be removed. The tongue or binder 98''' of this cell Z^9 , serves to hold the fresh shuttle until the location of the cell Z^9 at the shuttle race and the throwing of the shuttle by the driver 104' take place.

The cell Z^{10} shown in Fig. 6 in longitudinal section, has its rear wall, from its inner receiving end, made inclined outwardly, and extending at an angle to the rear wall of the other cells, so that the shuttle entering said cell may be conveniently removed by the weaver from the outer end thereof. The shuttle cell Z^{10} receives the shuttle to be exchanged when located in the shuttle race. In order that the brake action may be applied to the shuttle entering the cell Z^{10} , the rear wall of the cell is covered with a strip of leather 106, while the front of the cell is closed by a tongue 107. This tongue is constantly under the action of a spring 105 which for this purpose is arranged upon a rod 108 connected with the tongue 107 and adapted to bear on the one hand against an adjustable ring 109 upon this rod, and on the other hand against a guide 110 secured to the shuttle box.

In Fig. 1 the cell Z^{10} is shown as in line with the shuttle race C. To prevent the shuttle which is to be caught in the cell Z^{10} from flying out, I provide outside this cell on the carrier E of the lifting box provided with the guide for the latter a buffer 111, against which the shuttle is thrown when the brake action is insufficient. This buffer 111 is furnished with a soft cushion 114 and arranged at the free end of an arm 112 adapted to turn upon a horizontal bolt 113 on the box carrier E, so that the projecting arm can yield on receiving a blow from below (Figs. 4 and 6).

For guiding the change box B vertically, its vertical sides are provided with ledges 115, 115' adapted to engage with corresponding grooves in vertical guides 116, 116' on the change box carrier. This latter is se-

cured to the leg 117 of the lathe which is pivoted upon a pin 118 fixed below to the frame of the loom (Fig. 1).

The change box B is carried by a push rod 119 guided in an eye 120 on the change box carrier E. To the said push rod is connected, by means of the rod 121, one arm 122 of a bell crank lever 122, 123 arranged to turn upon a horizontal pin 124, on the frame of the loom (Figs. 2 and 3). The arm 123 of this bell crank lever is connected by a push rod 125 with an arm 126 fixed upon a transversely oscillating shaft 127 held in bearings at the lower part of the loom. On the left hand side of the loom the said transversely oscillating shaft 127 carries an arm 128 coupled by the push rod 129 with the lever 130 belonging to the shuttle box changing device and serving to place the cells in position. The lever 130 is fitted to turn upon a cross bolt 131 of an arm 132 which can oscillate upon a transverse shaft 133 firmly held upon the frame of the loom. Upon the cross-bolt 131 is moreover provided a two-armed lever 134, 135, the ends of which are connected through the medium of push rods 136 and 137, see Fig. 3, with bell-crank levers 138 and 139, the other arms 138' and 139' are jointed to push rods 140 and 140'. In like manner the lever 130 is connected by a push rod 141 with a bell-crank-lever 142, the other arm 142' of which is connected with a third push rod 140''. Each of the three push rods 140, 140', 140'' is jointed by its other end with the crank pin 143 of a toothed wheel or vibrator gear 144, 144', 144'' which is carried by a lever 145, 145', and 145'' respectively. All these vibrator levers turn upon a transverse shaft 146 firmly held in the frame of the loom, and are connected by springs 147 with the push rods 140. At its upper end each vibrator lever 145 is furnished with a triangular head 148 having one of its points directed upward, with which a ratchet lever 149 acts together in such a manner that it stops the vibrator lever in either of its two operative positions. The ratchet lever 149 is adapted to turn upon the pin 151 fixed to the frame of the loom, and has an arm 150 which under the action of a spring 152 is forced against a cam 153 arranged upon the shaft 154 and adapted to cause the release of the ratchet lever 149, in order to release the vibrator lever 145 for the purpose of enabling the latter to be moved from one position to the other.

The vibrator levers oscillate between two toothed drums 155, 156, the former of which is arranged upon the shaft 154, and the latter upon the shaft 157. The shafts 154 and 157 are actuated from the driving shaft 24 of the loom through the agency of toothed wheels 158, 159, 160, 161, 162, 163, the latter two being arranged upon the shafts 154 and 157, and the wheels 159, 160, 161 upon pins fixed

to the frame of the loom, while the wheel 158 is secured to the driving shaft 24.

Each of the aforesaid toothed drums 155, 156 is provided with teeth only upon half the periphery, the division of the teeth corresponding to that of the wheels 144 on the wheel-carrying levers. The shafts 154 and 157 with the toothed drums 155, 156, as indicated by the arrows I and II, Fig. 3, turn in opposite directions. When the vibrator levers 145, as in Fig. 3, occupy such a position that their wheels 144 come into engagement with the toothed drum 156, half a revolution will be imparted to them in the direction of the arrow III, thereby moving all the push rods 140 to their lowest position. In this case the insertion cell Z⁹ is placed in line with the shuttle race, because the drop box B passes to its lowest position. When all the vibrator levers occupy the other position, wherein the toothed drum 154 comes into gear with the toothed wheels 144 these toothed wheels will have communicated to them half a revolution in the opposite direction to that of the arrow III, and all the push rods 140 are moved to the highest position. Then the drop box B will be in the highest position and the catch cell Z¹⁰ will be at the height of the shuttle race (Fig. 3).

The movement of the vibrator levers to one or the other operative position, see Fig. 3, takes place by a blade 91 adapted to move constantly to and fro and by lifting wires 90, 90', 90'', of which each wheel-carrying lever has one. These lifting wires 90, 90' and 90'' are actuated in accordance with the pattern by a roller card 165 which is upon the cylinder 166. The roller card 165 acts upon levers 167, 168, 169 connected by wires 170, 170', 170'', see Fig. 1, with the lifting wires 90, 90', 90'' and submitted to the action of springs 171 which force the levers against a stop 172 limiting their downward movement. The movement of the cylinder 166 is controlled by a turning hook 173, the rod of which is connected with a bell crank lever 174, 175, adapted to turn upon a fixed pin 176 and moved through the medium of an eccentric 178 on the driving shaft of the loom.

In addition to the customary mode of acting upon the lifting wires 90, 90', 90'' I provide according to this invention for the second mode of acting upon the same by the controlling device, whereby only the location of the cells Z⁹ and Z¹⁰ in the shuttle race is effected. This latter device will hereinafter be more particularly set forth.

For placing the special cells in position, in addition to the seven lifting hooks P¹, P², P³, P⁴, P⁵, P⁶, P⁷, corresponding to the seven shuttles, I employ another lifting hook P⁰. This lifting hook P⁰ is joined to the lever 2 designed for placing the insertion cell Z⁹ in the shuttle race. By the

shaft 3 mounted in the frame of the mechanism, the lever 2 is firmly connected with a lever 4 which, in opposition to the action of a spring 21, Figs. 1, 8, 9, 10, 11, transmits the operative movement of the lifting hook P^0 , through the draw-rod 5, Figs. 1 and 8, 9, 10, 11, the bell-crank lever 6, 7, adapted to turn upon the pivot 10, the draw-rod 8, lever 9, shaft 11, lever 12, push-rod 13, Fig. 1, and the lifting-wire lever 14, 18 adapted to turn upon the fixed bolt 16, to the lifting-wire 90 of the drop mechanism, in order to lift it from the blade 91, whereby the insertion cell Z^0 is placed in line with the shuttle race.

The movement of the blade 17 of the controlling device takes place, and also that of the supporting arm 19 of the cylinder 31 for the controlling card, from the oscillating shaft 20 supported in the frame of the mechanism. This shaft is actuated by an eccentric 23, Figs. 1 and 3, from the driving shaft 24 of the loom. Upon the oscillating shaft 20 are arms 25 connected by push-rods 26 with the supporting arm 19 of the cylinder 31, and arms 27 connected with the blade 17 by means of push-rods 28. To one of the arms 27 is also connected the rod 29 of the eccentric 23, Fig. 1.

The operative movement of the lifting hooks $P^1, P^2, P^3, P^4, P^5, P^6, P^7$, is transmitted to the lifting wire 90 by the frame 32 fixed upon an oscillating shaft 30 and having a lower transverse rod 33 on which the lifting hooks $P^1, P^2, P^3, P^4, P^5, P^6, P^7$, are pivotally mounted. The oscillatory movement of the shaft 30 is transmitted by the arm 34 also fixed upon it, the draw-rod 35, the bell-crank lever 36, 37, adapted to turn upon the pivot 10, the draw-rod 38 and the arm 40 of the two-armed lever 39, 40 on the shaft 11 to the lifting wire 90 in the direction in which the same is hooked to the blade 91, whereby the cell Z^{10} for a shuttle to be removed, is placed in position. A spring 41, see Fig. 1, acts upon the bell-crank lever 36, 37 in opposition to the operative movement of the lifting hooks $P^1, P^2, P^3, P^4, P^5, P^6, P^7$ on the frame 32. By a fixed stop 22 the movement of the aforesaid frame 32 is limited in the direction of the action of the spring 41, see Fig. 8.

A locking device is provided for each of the lifting hooks $P^1, P^2, P^3, P^4, P^5, P^6, P^7$, this device being adapted to be released by hand. The devices may for instance consist of stop levers 53, which, being arranged to be turned upon a common fixed shaft 46, take below the respective lifting hooks $P^1, P^2, P^3, P^4, P^5, P^6, P^7$, and are usually raised by springs 42 to such an extent that the lifting hooks $P^1, P^2, P^3, P^4, P^5, P^6, P^7$ bearing upon them cannot engage with the blade 17. The action of the springs 42 upon the levers 53 is limited by stops 43 on the indicating

spindles $W^1, W^2, W^3, W^4, W^5, W^6, W^7$ bearing against corresponding ribs 44 on the frame of the mechanism. The indicating spindles $W^1, W^2, W^3, W^4, W^5, W^6, W^7$ are rotatably mounted, and have the disks or engaging surfaces on their front ends, see Figs. 1, and 2, which are furnished with numbers, in this instance, 1, 2, 3, 4, 5, 6, and 7, corresponding to the number of operative shuttle box cells. Each rotatable spindle $W^1, W^2, W^3, W^4, W^5, W^6, W^7$ has secured thereon a crank 45, which is pivotally connected with a rod or connector $N^1, N^2, N^3, N^4, N^5, N^6, N^7$, see Fig. 8, to the stop levers 53.

For locking the stop levers 53 in their released position (at W^7 , Fig. 10), use is made of a stop bar 46' which by means of arms 47 is fixed upon an oscillating shaft 48 supported in the frame of the mechanism. The free ends of arms 49 firmly connected with the stop levers 53 pass behind the stop bar 46'. A stop bar 50 likewise arranged on the arms 47 of the stop bar 46' limits the releasing movement of the stop levers 53. The stop bar 46' is constantly forced to the locking position by a spring 55 attached to an arm 56 likewise fixed to the oscillating shaft 48. This device for locking the stop lever 53 in the released position is liberated by the corresponding lifting hook $P^1, P^2, P^3, P^4, P^5, P^6, P^7$ in the operative movement of the same, a lever arm 93, see Fig. 8, secured upon the oscillatory shaft 30 being adapted to act upon a lever arm 94 which together with the stop bar 46' is fixed upon the oscillatory shaft 48. The stop lever thus left to the action of its spring 42 returns to its operative position and raises the corresponding lifting wire again out of the reach of the blade 17. In the same manner as the lifting hooks $P^1, P^2, P^3, P^4, P^5, P^6, P^7$, the lifting wire P^0 is usually kept out of engagement with the blade 17. This is effected by a bell-crank lever 51, 71 arranged to turn upon the shaft 48, and the arm 51 of which is subjected to the action of a draw-spring 52 secured to the frame of the mechanism. The free end of the arm 51 engages by a pin 96 with a longitudinal slot 54 in the lifting wire P^0 and usually holds the latter from engagement with the blade 17.

For hooking the lifting wire P^0 to the blade 17, a turning movement of the bell-crank lever 51, 71 is accordingly required to take place in opposition to the action of the spring 52. This turning movement is imparted to the bell-crank lever 51, 71 by a motive-power device which is put in tension only in the operative movement of one of the lifting hooks $P^1, P^2, P^3, P^4, P^5, P^6, P^7$. This motive power device consists of the spring 55 which on the one hand, as before stated, is attached to the arm 56 upon the oscillatory shaft 48 and on the other hand to a frame 58, arranged to turn upon a shaft 57

fixed in the frame of the mechanism. The lower transverse side of the frame 58, is arranged in front of the blades 17 and usually bears against intermediate levers 60, 61, 62, 5 63, 64, 65, 66, which have a common fixed stop consisting of a bar 95, see Fig. 8, serving as an abutment in opposition to the action of the spring 55, and which correspond each to a lifting hook P¹, P², P³, P⁴, 10 P⁵, P⁶, P⁷. These lifting hooks are furnished at their heads with extensions 67 which on the termination of the operative movement of the lifting hooks engage with corresponding notches 68 in the intermediate levers 60, 15 61, 62, 63, 64, 65, 66, thus causing the respective intermediate levers together with the frames 58, to swing in opposition to the action of the spring 55. In this movement a lifting wire 70 jointed to an upwardly extending arm 69 of the frame 58, engages 20 with the free knife-shaped end of the arm 71 of the bell-crank lever 51, 71 adapted to turn loosely upon the oscillatory shaft 48.

In order that the frame 58 may not, in the 25 return movement of the lifting hooks P¹, P², P³, P⁴, P⁵, P⁶, P⁷, at once give way to the action of the spring 55, it is locked in the position to which it has been moved, and wherein the spring 55 is quite under tension, through 30 the agency of a stopping device which may be released by the second controlling card provided for placing the insertion cell Z⁹ in line with the shuttle race or, as in the constructional form shown by way of example, 35 by the second row of needles of the controlling card 31. For this purpose the intermediate levers 60, 61, 62, 63, 64, 65, 66, 67 have at their lower end a lateral projection 72, and for each of the intermediate levers 60, 61, 62, 40 63, 64, 65, 66 I provide a stop lever having three arms 73, 74, 75, these levers being arranged to turn upon a common shaft 76. The arm 73 of the stop lever 73, 74, 75 forms a hook which seizes and holds the projection 45 72 of the intermediate lever which has swung outward. To the arm 75 is attached the end of a spring 77, the other end of which is secured to an arm 78 of the corresponding intermediate lever, forcing the latter to the 50 position of rest, but the stop lever to the operative position. The third arm 74 of the stop lever 73, 74, 75 is connected by a draw-rod 79 with the corresponding needle levers 80, 81, 82, 83, 84, 85, 86 of the second row of 55 needles N¹, N², N³, N⁴, N⁵, N⁶, N⁷, in such a manner that it takes part in the swinging movement of the respective needle lever on the corresponding needle being forced back in the direction of the arrow, Figs. 8, 10, 11. By 60 this means the locking device 72, 73 is released, and the spring 55 becomes free. By the turning movement of the oscillatory shaft 48 through the medium of the frame 58, the arm 69 of this frame, the lifting wire 70 and

the lever 71, the said spring causes the lifting 65 hook P⁰ to be hooked to the blade 17.

Like the lifting hooks P¹, P², P³, P⁴, P⁵, P⁶, P⁷, the lifting wire P⁰ is unhooked automatically at the end of its operative movement. For this purpose the shaft 3 of the lifting-wire 70 lever 2 carries a third arm 87 having a pin 88 adapted to engage with a slot 89 in a draw-rod 92 jointed to the lifting wire 70. By reason of this slot connection the arm 87 may have an independent upward motion, until at the 75 end of its upward movement it unhooks the lifting wire 70, and the lever 71 is turned by the spring 52 so much farther in the direction wherein the lifting wire P⁰ is unhooked that the hook of the lifting wire 70 on falling back 80 cannot take behind the same (Fig. 8).

The controlling cards 31', Figs. 7 and 8, are punched to follow the shuttles, and each card has two indications for each shuttle, and two needles for each shuttle are operated 85 by and under the control of the cards. One set of needles, in this case, the lower set of needles, N¹, etc., engage one end and have under their control a set of angle levers 15, one of which levers is shown in Fig. 8; the 90 opposite end of the lever 15 forms one support for a hook P⁷. The hook P⁷ has also a second support 53. Both of these supports 15 and 53 must be lowered so that the hook P⁷ may drop and be engaged by the reciprocating blade 17, as it is moved forward. Said blade 17 has a constant reciprocating movement. The hook P⁷, when it is allowed 95 to drop and engage the blade 17, is pulled forward, and rocks the lever 32 about its fulcrum, which operates the lever 34, having attached to its end the hook connector 35. The hook connector 35 is connected with mechanism on the box motion end of the 100 loom, which has been hereinbefore fully described, to cause the necessary vibrator levers to be brought into action to cause the lower cell Z¹⁰ to be raised in line with the 105 shuttle race, to receive the shuttle to be removed. 110

The operation for inserting a new shuttle will be as follows:—When the time comes for the insertion of a new shuttle having filling corresponding to the filling in the shuttle removed, the blank space in the card of the 115 pattern chain 31' which corresponds with the shuttle to be inserted, will be operative to push a needle N¹ back, and rock the lever 80 about its fulcrum, causing the attached connector 79 to rock the latch lever 120 73 about its fulcrum, and release the latch 73 from the hook 72 on the frame 58, which frame will then be moved inwardly by the spring 55, causing the lever 69 to be moved outwardly, and through connector 70 to 125 rock the angle lever 71, and cause the lever 71 to lower the hook P⁰ in the path of the blade 17. On the outward movement of

said blade 17, the hook P^0 is carried forward, rocking the lever 2, shaft 3, lever 4, and connector 5 to the proper vibrator levers on the box motion end of the loom, to cause the 5 said vibrator levers to lower the box cells, and to bring the spare shuttle cell Z^0 to the line of the race for the insertion of a new shuttle. By the arm 87, fast on the shaft 3, and the draw rod 92, the connector 70 is 10 raised, and the lever 71 unhooked; the spring 52 acts to rock the lever 51, and raise the hook P^0 out of the path of the reciprocating blade 17, and it remains in this position until another shuttle is to be removed, 15 and then the operation is repeated. The forward movement of the hook P^0 causes the end of the hook P^0 to engage the V shaped recess 68 in the frame 58 and move outwardly said frame and the projection 72 thereon until said projection 72 engages the 20 notch on the lever 73, see Fig. 8; to lock said frame in its outward position, ready to be released as above described.

It will be observed, that it is necessary for 25 one of the hooks, marked P^1 , P^2 , P^3 , P^4 , P^5 , P^6 , P^7 , to be lowered into the path of the reciprocating blade 17, to cause the first operation, to wit,—the movement of the cell Z^0 , to receive a shuttle to be removed, to the 30 line of the race-way. As these hooks, P^1 , P^2 , P^3 , P^4 , P^5 , P^6 , P^7 , have two supports, it is necessary that both supports should be lowered out of the way of said hooks, before they are dropped on the reciprocating blade 35 17. One of these supports, 15, as above stated, is under the control of the set of cards 31', which continuously follow the shuttles in their operation, and therefore the said support, corresponding to the shuttle 40 being at the time in operation, will be lowered by the cards each time a shuttle is picked. The other set of supports 53 are under the control of the hand operated spindles W^1 , W^2 , W^3 , W^4 , W^5 , W^6 , W^7 , therefore 45 when one of the supports 53 is lowered from a hook P^1 , etc., by a partial rotation of the spindles W^1 , W^2 , W^3 , W^4 , W^5 , W^6 , W^7 , and the corresponding shuttle and the corresponding indication on the cards 31' comes 50 into position with the needles, marked N^1 , N^2 , N^3 , N^4 , N^5 , N^6 , N^7 , and lowers the other support 15, corresponding to the support 53, which has been lowered through the turning 55 of a spindle W^1 , W^2 , W^3 , W^4 , W^5 , W^6 , W^7 , the hook P^1 , P^2 , P^3 , P^4 , P^5 , P^6 , P^7 , commonly held up by the two supports 53 and 15, will be lowered, and will be allowed to catch the blade 17 on its forward movement.

From the above description it will be plain, 60 that each hook P^1 , P^2 , P^3 , P^4 , P^5 , P^6 , P^7 , is under the automatic control of a card of the chain 31', and also under the control of one of the spindles W^1 , W^2 , W^3 , W^4 , W^5 , W^6 , W^7 , to be manually operated.

65 The advantages of my improvements will

be readily appreciated by those skilled in the art. I provide mechanism, which has therein and as a part thereof, a set of indicators, as the spindles W^1 — 7 , to be operated by hand at the option of the weaver, the 70 operation of which will, through mechanism connected therewith, cause the particular shuttle indicated, which may be any one of the shuttles, the next time said shuttle is called into operation, to run into a special cell from which it can be easily removed by hand, and also to bring into operation a 75 fresh shuttle which has previously been placed in a special cell for the purpose.

It will be understood that the details of 80 construction of my improvements may be varied if desired, and they may be adapted to be applied to looms of ordinary and well known construction, with change or drop shuttle boxes, at one, or both ends of the loom. 85

I have used herein the words manually controlled, in connection with the means for operating the shuttle boxes, but it will be understood that I do not limit myself to a manual or hand controlled means, as I may substitute foot controlled means, with a foot pedal, etc. I intend to cover broadly in the claims, non-automatic means, as distinguished from automatic.

What I claim as my invention, and desire 95 to secure by Letters Patent, is:—

1. In a loom, the combination with drop shuttle boxes at both ends of the loom, of 100 manually controlled means for operating the shuttle boxes at one end of the loom.

2. In a loom, a lay, drop shuttle boxes at both ends of the lay, one set of shuttle boxes having a cell for the shuttle to be removed, and manually controlled means for bringing 105 said cell in line with the race-way.

3. In a loom, a lay, drop shuttle boxes at both ends of the loom, one set of shuttle boxes having two special cells, said cells connected to and moving with said shuttle boxes, and one cell adapted to receive the shuttle to 110 be removed, and the other cell to introduce the fresh shuttle, and manually controlled means for effecting the operation of the drop shuttle boxes having the two special cells.

4. In a loom, a lay, a cell for the shuttle to 115 be removed from the loom mounted thereon, and movable at all times with the lay, a drop shuttle box to contain a running shuttle, and manually controlled means to bring said cell to the line of the race-way to receive 120 the shuttle to be removed.

5. In a loom, a lay, a shuttle box for the running shuttle, and a shuttle box for the 125 spare shuttle, both moving at all times with the lay, and manually controlled means for effecting the operation of the shuttle box for the spare shuttle.

6. In a loom, a lay, a shuttle cell for the running shuttle, a cell for the spare shuttle, and a cell for the shuttle to be removed from 130

the loom, said cells moving at all times with the lay, and manually controlled means for effecting the operation of the cell for the spare shuttle, and the cell for the shuttle to be removed from the loom.

5 7. In a loom, a lay, drop shuttle boxes, a cell adapted to receive the shuttle to be removed, a cell adapted to supply a fresh shuttle, mechanism for positioning said drop shuttle boxes and said cells, pattern indicating mechanism for the drop shuttle boxes, and connections intermediate said pattern indicating mechanism, and a second pattern indicating mechanism for said cells, and said 10 second indicating mechanism having indications for said receiving cell, and separate indications for said supplying cell.

8. In a loom, a lay, drop shuttle boxes at both ends of the lay, a cell adapted to receive 20 the shuttle to be removed, a cell adapted to supply a fresh shuttle, mechanism for positioning said drop shuttle boxes and said cells, pattern indicating mechanism for the drop shuttle boxes, and connections intermediate 25 said pattern indicating mechanism, and a second pattern indicating mechanism for said cells, and said second indicating mechanism having indications for said receiving cell, and separate indications for said 30 supplying cell.

9. In a loom, a lay, drop shuttle boxes at both ends of the lay, a cell adapted to receive the shuttle to be removed, a cell adapted to supply a fresh shuttle, manually controlled 35 means for positioning said drop shuttle boxes and said cells, pattern indicating mechanism for the drop shuttle boxes, and connections intermediate said pattern indicating mechanism, and a second pattern indicating mechanism for said cells, and said 40 second indicating mechanism having indications for said receiving cell, and separate indications for said supplying cell.

10. In a loom, a lay, drop shuttle boxes at 45 both ends of the lay, a cell adapted to receive the shuttle to be removed at one end of the lay, a cell adapted to supply a fresh shuttle at the same end of the lay, manually controlled means for operating said shuttle boxes 50 and said cells at one end of the lay, pattern indicating mechanism for the drop shuttle boxes, and connections intermediate said pattern indicating mechanism, and a second pattern indicating mechanism for said cells, 55 and said second pattern indicating mechanism having indications for said receiving cell, and separate indications for said supplying cells.

11. In a loom, a lay with drop shuttle 60 boxes, two special cells connected with the shuttle boxes on one end of the lay, one of these cells being adapted for catching the shuttle to be removed, and the other cell for introducing the fresh shuttle, a guide for the 65 shuttle box arranged to be moved up and

down and provided with the special cells, a shuttle changing mechanism for lifting and lowering the shuttle box with the special cells, and a device for actuating the shuttle changing mechanism for each of the successive 70 locations of the two special cells.

12. In a loom, a lay with drop shuttle boxes, two special cells connected with the shuttle boxes on one end of the lay, one of these cells being adapted for catching the 75 shuttle to be removed, and the other cell for introducing the fresh shuttle, a guide for the shuttle box arranged to be moved up and down and provided with the special cells, a shuttle changing mechanism for lifting and 80 lowering the shuttle boxes with the special cells, a card cylinder for the said shuttle changing mechanism, a card cylinder for the device for actuating the shuttle changing mechanism for each of the successive 85 locations of the special cells, turning hooks adapted for moving the card cylinders synchronously, and two sets of needles for the second card cylinders, each set corresponding to a definite cell of the special cells. 90

13. In a loom, a lay with change boxes, two special cells connected with the change boxes on one end of the lay, one of these cells being adapted for catching the shuttle to be removed, and the other cell for introducing 95 the fresh shuttle, a shuttle changing mechanism for locating the change boxes, means for locating the shuttle changing device for each of the special cells, and means for insuring the proper order of this location. 100

14. In a loom, a lay with change boxes, two special cells firmly connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the shuttle change 110 mechanism for locating the catch cell, a set of needle levers whereon the set of lifting wires bear, springs adapted to force the needle levers to their operative position, a set of needles arranged to act upon the needle levers in opposition to the springs, a lifting wire arranged for locating the insertion cell, means adapted for keeping this lifting wire out of engagement with the said blade, a motive power device arranged for placing the 115 lifting wire upon the blade, means for winding up the motive power device by the set of lifting wires, and means for releasing the motive power device by the second set of needles. 120

15. In a loom, a lay with change boxes, two special cells connected with the change boxes on one end of the lay, one of the said cells being adapted for catching the shuttle to be removed, and the other cell for intro- 130

- ducing the fresh shuttle, a shuttle changing mechanism for locating the change boxes, a blade, means for moving this blade to and fro, a set of lifting wires corresponding to the number of shuttles of the shuttle change mechanism for locating the catch cell, a set of needle levers whereon the set of lifting wires bear, springs adapted to force the needle levers to their operative position, a set of needles arranged to act upon the needle levers in opposition to the springs, a lifting wire arranged for locating the insertion cell, means for keeping this lifting wire out of engagement with the said blade, a bell-crank lever from one arm of which the said lifting wire is suspended, the said arm being submitted to the action of the releasing spring, a motive power device for placing the lifting wire upon the blade, means for winding up the motive power device by the set of lifting wires, and means for releasing the motive power device by the second set of needles.
16. In a loom, a lay with change boxes, two special cells connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the change mechanism for locating the catch cell, a set of needle levers whereon the set of lifting wires bear, springs adapted to force the needle levers to their operative position a set of needles arranged to act in opposition to the springs upon the needle levers, a lifting wire arranged for locating the insertion cell, means for keeping this lifting wire out of engagement with the said blade, a bell-crank lever from one end of which the said lifting wire is suspended, the said arm being submitted to the action of the releasing spring, and the other arm carrying a stop nose, an oscillating frame, a spring arranged to impart operative movement to the said frame, an arm firmly connected with the oscillating frame, a hooked lifting wire jointed to the said arm and adapted for taking hold of the stop nose, means for winding up the aforesaid spring of the oscillating frame by the set of lifting wires, and means for releasing the said spring by the second set of needles.
17. In a loom, a lay with change boxes, two special cells connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the shuttle change mechanism for locating the catch cell, a set

of needle levers whereon the said lifting wires bear, springs adapted to force the needle levers to their operative position, a set of needles arranged to act upon the needle levers in opposition to the springs, a lifting wire arranged for locating the insertion cell, means for keeping this lifting wire out of engagement with the said blade, a bell-crank lever from one end of which the said lifting wire is suspended, the said arm being submitted to the action of the releasing spring, and the other arm carrying a stop nose, an oscillating frame, a spring arranged to impart operative movement to the said frame, an arm firmly connected with the oscillating frame, a hooked lifting wire jointed to the said arm and adapted for taking hold of the stop noses, a set of intermediate levers corresponding to the set of lifting wires, arranged between this set and the said frame and bearing against the latter, and means for releasing the said spring of the oscillating frame by the second set of needles.

18. In a loom, a lay with change boxes, two special cells connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the shuttle change mechanism for locating the catch cell, a set of needle levers whereon the set of lifting wires bear, springs adapted to force the needle levers to their operative position, a set of needles arranged to act upon the needle levers in opposition to the springs, a lifting wire for placing the insertion cell, means for keeping this lifting wire out of engagement with the said blade, a bell-crank lever from one end of which the said lifting wire is suspended, the said arm being submitted to the action of the releasing spring, and the other arm carrying a stop nose, an oscillating frame, a spring arranged to impart operative movement to the said frame, an arm firmly connected with the oscillating frame, a hooked lifting wire jointed to the said arm and adapted for taking hold of the stop nose, means for winding up the aforesaid spring of the oscillating frame by the set of lifting wires, and means for releasing the said spring by the second set of needles.

19. In a loom, a lay with change boxes, two special cells connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the shuttle change mechanism for locating the catch cell, a set

- to be removed, and the other cell for introducing the fresh shuttle, a shuttle changing mechanism for locating the change boxes, a blade, means for moving this blade to and fro, a set of lifting wires corresponding to the number of shuttles of the change mechanism for locating the catch cell, a locking device for each of the lifting wires and means for releasing the several locking devices by hand.
- 10 20. In a loom, a lay with change boxes, two special cells connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the change mechanism for locating the catch cell, a locking lever designed for each of the lifting wires of the aforesaid set and arranged to take below the corresponding lifting wires, a fixed shaft upon which the locking levers are adapted to turn, springs adapted to force the locking levers against the said lifting wires, stops designed for the locking levers and adapted for limiting the action of the springs, and means for releasing the several locking devices by hand.
- 15 25. In a loom, a lay with change boxes, two special cells connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the change mechanism for locating the catch cell, a locking lever designed for each of the lifting wires of the aforesaid set and arranged to take below the corresponding lifting wires, a fixed shaft upon which the locking levers are adapted to turn, springs adapted to force the locking levers against the said lifting wires, stops designed for the locking levers and adapted for limiting the action of the springs, and means for releasing the several locking devices by hand.
- 30 35. In a loom, a lay with change boxes, two special cells connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the change mechanism for locating the catch cell, a locking lever for each of the lifting wires of the aforesaid set and arranged to take below the corresponding lifting wires, a fixed shaft upon which the locking levers are adapted to turn, springs adapted to force the locking levers against the said lifting wires, stops designed for the locking levers and adapted for limiting the action of the springs, releasing spindles, handles on the spindles for turning the same, cranks fixed upon these spindles, and push rods connecting these cranks and the said locking levers.
- 40 45. In a loom, a lay with change boxes, two special cells connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the change mechanism for locating the catch cell, a locking lever for each of the lifting wires of the aforesaid set and arranged to take below the corresponding lifting wires, a fixed shaft upon which the locking levers are adapted to turn, springs adapted to force the locking levers against the said lifting wires, stops designed for the locking levers and adapted for limiting the action of the springs, releasing spindles, handles on the spindles for turning the same, cranks fixed upon these spindles, and push rods connecting these cranks and the said locking levers.
- 50 55. In a loom, a lay with change boxes, two special cells connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the change mechanism for locating the catch cell, a locking lever for each of the lifting wires of the aforesaid set and arranged to take below the corresponding lifting wires, a fixed shaft upon which the locking levers are adapted to turn, springs adapted to force the locking levers against the said lifting wires, stops designed for the locking levers and adapted for limiting the action of the springs, releasing spindles, handles on the spindles for turning the same, cranks fixed upon these spindles, and push rods connecting these cranks and the said locking levers.
- 60 65. In a loom, a lay with change boxes, two special cells connected with the change boxes on one end of the lay, one of the said cells being adapted for catching the shuttle to be removed, and the other cell for introducing the fresh shuttle, a shuttle changing mechanism for locating the change boxes, a blade, means for moving this blade to and fro, a set of lifting wires corresponding to the number of shuttles of the change mechanism for locating the catch cell, a locking lever for each of the lifting wires of the aforesaid set and arranged to take below the corresponding lifting wires, a fixed shaft upon which the locking levers are adapted to turn, springs adapted to force the locking levers against the said lifting wires, means for releasing the several locking devices by hand, arms provided on the locking levers, a locking rod for holding the said arms in the released position, arms to which this locking rod is secured, a shaft arranged parallel to that of the locking levers and whereon the said arms are arranged to turn, and a spring adapted to force the said locking rod to its locking position.
- 70 75. In a loom, the combination with change shuttle boxes at each end of the loom, and two additional shuttle box cells at one end of the loom, one adapted to receive the shuttle to be removed, and the other to hold the fresh shuttle to be introduced, and means for operating the shuttle boxes, of mechanism for bringing into position, in line with the shuttle race, the shuttle box cell to receive the shuttle to be exchanged, and the shuttle box cell for introducing the fresh shuttle, the operation of said mechanism controlled by the manual operation of the weaver, and connections intermediate said mechanism and said shuttle box cells.
- 80 85. In a loom, the combination with change shuttle boxes at one end of the loom, and two additional shuttle box cells at the same end of the loom, one adapted to receive the shuttle to be removed, and the other to hold the fresh shuttle to be introduced, of mechanism for bringing into position, in line with the shuttle race, the shuttle box cell to receive the shuttle to be exchanged, and the shuttle box cell for introducing the fresh shuttle, the operation of said mechanism controlled by the manual operation of the weaver, when desired, and connections intermediate said mechanism and said shuttle box cells.
- 90 95. In a loom, the combination with change shuttle boxes at one end of the loom, and two additional shuttle box cells at the same end of the loom, one adapted to receive the shuttle to be removed, and the other to hold the fresh shuttle to be introduced, of mechanism for bringing into position, in line with the shuttle race, the shuttle box cell to receive the shuttle to be exchanged, and the shuttle box cell for introducing the fresh shuttle, the operation of said mechanism controlled by the manual operation of the weaver, when desired, and connections intermediate said mechanism and said shuttle box cells.
- 100 105. In a loom, indicators to be operated by hand at the option of the weaver, and mechanism connected with said indicators, to cause the particular shuttle indicated, the next time said shuttle is called into operation, to run into a special box cell, and also to cause a fresh shuttle, previously placed in a special box cell, to be brought into operation.
- 110 115. In a loom, a lay, a movable shuttle box having a plurality of cells, one above the other, and one of said cells adapted to have the shuttle manually inserted or removed through the outer end thereof.
- 120 125. In a loom, a lay, a movable shuttle box having a plurality of cells, one above the other, and one of said cells adapted to have a shuttle manually inserted or removed through the upper side thereof.
- 130 135. In a loom, a lay, a movable shuttle box having a plurality of cells, one above the other, and one of said cells adapted to have a shuttle manually inserted or removed through the upper side thereof.

other, and one of said cells adapted to have a shuttle manually inserted or removed through the upper side thereof, and one of said cells adapted to have a shuttle manually inserted or removed through the outer end thereof.

29. In a loom, a lay, a plurality of cells for the shuttles at one end of the lay, said cells arranged one above the other, and having a vertical reciprocating movement, and one of said cells adapted to have a shuttle manually inserted or removed through the upper side thereof, and one of said cells adapted to have a shuttle manually inserted or removed through the outer end thereof.

30. In a loom, a lay, a movable shuttle

box, comprising a plurality of cells, one above the other, the upper cell provided with an opening in its top for the manual insertion or removal of a shuttle, and the lower cell provided with an opening in its front for the manual insertion or removal of a shuttle, and means for bringing either of said cells into alignment with the race-way of the lay as desired.

In testimony whereof I have signed my name to this specification in the presence of two subscribing witnesses.
